UNITED STATES PATENT OFFICE.

ELMER E. COPE, OF DUBOIS, PENNSYLVANIA.

LUBRICATOR.

1,014,568.

Specification of Letters Patent.

Patented Jan. 9, 1912.

Application filed May 26, 1911. Serial No. 623,555.

To all whom it may concern:

Be it known that I, ELMER E. COPE, a citizen of the United States, and a resident of Dubois, in the county of Clearfield and 5 State of Pennsylvania, have invented a new and Improved Lubricator, of which the following is a full, clear, and exact description.

My invention relates generally to lubricators or lubricating devices and more particularly it involves an improved form of construction especially adapted for use with the air cylinders of air pumps or compressors and more particularly on the air cylinder of an air pump on a locomotive.

15 The object of my invention is to provide a new and improved lubricating means for the air cylinder of an air pump which may be placed in the cab of a locomotive and which will feed the lubricating material to 20 the cylinder only when the pump is working.

A further object of my invention is to provide a new and improved form of lubricating device especially adapted for use on locomotives for lubricating the air cylinder of the air compressor, the device being provided with a suitable means whereby the lubricating material is fed uniformly and in any desired amount, the lubricating material being maintained in a suitable chamber 25 free from the pressure of the air cylinder, and being supplied to the cylinder intimately mixed with the air and in fine particles.

It has been a difficult matter to properly 35 lubricate the air cylinder of an air compressor on account of the varying pressure of the air within this cylinder, most of the devices previously in use being affected in their operation by this varying pressure being communicated thereto; in my improved 40 form of device I make use of this varying pressure as the actuating means for effecting the feed of the lubricating material to the air cylinder.

45 Reference is to be had to the accompanying drawings, forming a part of this specification, in which like characters of reference denote corresponding parts in all the views, and in which—

50 Figure 1 is a side view of a locomotive showing the location of my device in the cab thereof; Fig. 2 is a vertical sectional view of the lubricator; Fig. 3 is a top plan view thereof; Fig. 4 shows a slightly modified form of construction.

A suitable body member 1 is provided

with an oil chamber 2, the bottom of this chamber being provided with a suitable bushing 3 having an opening therein through which the feed rod 4 passes, the lower end 5 of this rod being outwardly flaring and being adapted to seat itself within the tapered opening 6 in the outer portion of the bushing; the rod is maintained in this position by means of a helical spring 5 surrounding it and engaging in suitable nut or other locking device 7 in engagement with the rod whereby the pressure of the spring is transmitted directly to the rod. The feed rod 4 passes upwardly through a suitable sleeve 8 having an opening 9 in its lower end which communicates with a suitable pocket 10 in the side of this rod, the opening and the pocket registering when the parts are in the position shown in Fig. 2. The rod 75 is also provided with a suitable laterally extending pin 4' which engages in a vertically extending groove or slot in one side of the sleeve 8 whereby the rod is held against turning in its travel. Another chamber 11 is suitably positioned within the body member 1, this chamber being provided with a piston 12 having a suitable packing ring 13 therein, the piston rod 14 extending upwardly and beyond the top of this chamber. 80 The lower end of the body portion is provided with a suitable outlet 15 adapted to be placed in communication with the cylinder of the pump or compressor, this outlet communicating with the pipe 16 which leads 90 to the chamber 11, there being a suitable chamber 17 in the bottom of the body member containing the valve 18 seated therein; this valve is maintained in position by having the stem thereof engaged in the slot 19 95 provided in the plug 20 which is in removable engagement with the body member, the valve partaking of an upward and downward movement within this chamber; a suitable spring 100 maintains the valve normally 100 in the position shown in Fig. 2.

Directly under the oil chamber 2 and also contained within the body member 1 is the cavity 21 having the air outlet 22, the lower end portion of the feed rod 4 extending into this cavity and the lower portion thereof being provided with a plug 23 having openings 24, 24', therein, which communicate with the chamber 17, this plug 23 forming, in effect, a seat for the valve 18 positioned 110 thereunder.

The oil chamber 2 and chamber 11 con-

tained in the body member are covered by any suitable member 25 held in position preferably by means of removable screws 6, this cover being provided with suitable openings whereby the upper end 27 of the feed rod may project therethrough as well as the upper end 28 of the piston rod 14 contained in the chamber 11. I have shown the chambers 11 and 17 in communication by means of a pipe 16, but, of course, it is obvious that instead of using this pipe I may provide any suitable equivalent structure; if the pipe is used, however, suitable bushings are used to insure a tight connection.

18. The cover 25 is provided with a bearing 29 through which a spindle 30 passes, one end of the spindle having the dog 31 thereon held in adjustable position by means of a set screw 32, the outer end of the dog engaging the upper end portion 27 of the feed rod 4; the other end of this spindle is provided with the dog 33 held in adjustable position by means of a set screw 34, the outer end of this dog engaging the upper end 28 of the piston rod 14. In order to regulate the amount of oil fed to the cylinder I have provided a regulating device made up of the supporting member 35, having the set screw 36 therein, together with 30 a locking nut 37, whereby the position of the lower end of this set screw 36 may be determined.

The use and operation of my device is as follows: The lubricator shown in Fig. 2 is set up in any desired position and preferably within the cab of the locomotive, as shown in Fig. 1. The pipe from the outlet 15 is connected to the air cylinder of the compressor and the oil chamber 2 is filled with a desired amount of oil by turning the removable cap 40 which uncovers the opening 41 in the cover 5. When the compressor begins to work and when the air within the air cylinder is being compressed, the pressure is transmitted through the pipe to the outlet 15 and will force the valve 18 in the chamber 17 into closed position as shown in Fig. 2, this pressure also communicating with the piston 12 in the chamber 11, therefore by forcing the piston rod 14 upwardly and turning the spindle 30 by means of the dog 33, such movement bringing the dog 31 at the opposite end thereof downwardly and moving the feed rod 4 so that the lower end 5 thereof is forced into the cavity 21; it has previously been stated that the pocket 10 adjacent the lower end of the feed rod and the opening 9 contained in the sleeve 8 are registering so that a suitable amount 60 of oil may find its way into this pocket 10 to be later discharged into the cavity 21 when the feed rod 4 moves down as just described. During the rarefaction of the air within the air cylinder of the compressor 65 on the next stroke of the piston the pres-

sure within the outlet 15 and the chamber 17 and the chamber 11 will be reduced and the spring 5 within the oil chamber 2 will bring the lower end of the feed rod 4 back to the position shown in Fig. 2, this reduction of 70 pressure also permitting the valve 18 to come out of engagement with the seat 23 whereby the oil previously discharged into the cavity 21 is permitted to flow out through the openings 24, 24', whence it is 75 drawn along into the air cylinder together with the air flowing therethrough, whereby the pressure is equalized, the air vent 22 communicating with the cavity 21 providing a 80 suitable source of this air. These operations just described are repeated during each compression and rarefaction stroke of the piston in the air cylinder of the compressor, the dogs 31 and 33 moving upwardly and downwardly, and since the lubricator is within 85 the cab such movement of these dogs is a convenient indicating means to those in the cab that the air compressor is working. By fixing the relation of the set screw 36 and the locking nut 37 with relation to the supporting member 35, the upward travel of the dog 33 is determined, this also determining the downward movement of the dog 31 and the travel of the feed rod 4, thereby 90 regulating the amount of oil to be fed into 95 the cavity 21 at each compression stroke of the compressor.

In place of the spindle with the dogs thereon, shown in Figs. 2 and 3, I have provided a modified form and means, as shown in Fig. 4, which comprises the lever 30' suitably pivoted at its central point to a spindle 29', the opposite ends of this lever or walking beam being adapted for engagement with the upper ends 27 and 28 of the feed rod 4 and the piston rod 14; the operation of my device when provided with this form of construction is not substantially different from the operation of the equivalent parts shown in Figs. 2 and 3, the purpose of the lever 30' or the spindle with the dogs thereon being merely to move the feed rod 4 down at certain intervals which are determined by the upward travel of the piston rod 13. The regulating device for determining the amount of travel of the feed rod 4 which embodies the set screw 36 with the lock nut 37 and the supporting member 35 may be conveniently retained in this form 110 of construction.

From a consideration of the structure and operation of my device it will be noted that by supplying the desired amount of lubricant to the cavity at stated intervals, which lubricant is carried on to the cylinder by the inrush of air supplied thereto, that this lubricant will be intimately mixed with the air and will be suspended therein in the form of small particles whereby it is bodily carried into the cylinder, not being allowed 125 130

to flow along the side walls of the pipe communicating therewith; the openings in the bottom of the cavity through which the mixture of air and lubricant pass have an atomizing effect whereby this very thorough commingling of the air and the lubricant is effected.

While I have shown a certain size and shape of my lubricating device, together with the component parts thereof, it is obvious that it may be large or small, depending on the use to which it is to be put, and that in place of the various elements shown I may supply their equivalents in a mechanical sense without departing from the spirit and scope of my invention as defined in the following claims.

Having thus described my invention, I claim as new, and desire to secure by Letters 20 Patent:-

1. In a device of the class described, a body member having a cavity therein, the cavity communicating with a suitable oil chamber and with the cylinder of a compressor, means movably mounted within the cavity and the oil chamber whereby a desired amount of oil may be passed from the chamber into the cavity, together with a valve between the cavity and the cylinder and operable by the differences of pressure within the cylinder, there being also other means operable by the differences of pressure within the cylinder for actuating the means within the oil chamber and the cavity whereby during operation of the compressor a desired amount of lubricant is fed thereto on each rarefaction stroke.
2. In a device of the class described, a body member having a cavity therein, the said cavity communicating with a suitable oil chamber and with the cylinder of a compressor, movable means within the cavity and the oil chamber whereby a desired amount of lubricant may be passed to the said cavity, a member movably mounted between the cavity and the compressor for closing the said communication on a compression stroke, and other means also actuated on the said compression stroke for actuating the means within the cavity and oil chamber to pass the desired amount of lubricant to the cavity, the said lubricant within the cavity being carried on to the compressor on a rarefaction stroke.
3. In a device of the class described a body member having a cavity therein, the said cavity communicating with an oil chamber, with the atmosphere, and with a compressor, movable means for passing a desired amount of lubricant from the chamber to the cavity, and a member movably positioned between the cavity and the compressor, the said member being in closed position on a compression stroke, and other means actuating the means for passing the lubricant from the
- chamber to the cavity also actuated on the compression stroke whereby, on a rarefaction stroke, communication between the cavity and the compressor being established, the lubricant contained within the cavity 70 may be drawn into the compressor.
4. In a device of the class described, a body member having a cavity therein, the said cavity communicating with a suitable oil chamber, with the atmosphere, and with 75 the air cylinder of a compressor, means contained within the cavity and the oil chamber whereby a desired amount of oil may be passed from the said chamber to the said cavity, together with means between the 80 cavity and the said air cylinder and operable by the differences of pressure within the said cylinder, means also operable by the differences of pressure within the cylinder for actuating the said means within the 85 oil chamber and the cavity, the said means between the cavity and the cylinder being movable to open position on a rarefaction stroke whereby the air may enter the cylinder through the cavity and there mix with 90 a desired amount of oil, the said means being closed on a compression stroke, the other means actuating the means in the oil chamber and cavity being actuated by the compression to feed a desired amount of oil 95 from the oil chamber to the cavity.
5. In a device of the class described, a body member having a cavity therein, together with a suitable oil chamber, means whereby a desired amount of lubricant may 100 be passed from the oil chamber to the cavity, the cavity communicating at its upper portion with the atmosphere, as an air supply, and communicating at its bottom portion with the air cylinder of a compressor, 105 means without the cavity and adapted to be moved in order to open and close the said communication with the cylinder, the said means being operable on a rarefaction stroke to open the communication whereby air may 110 enter the cylinder through the cavity and carry with it an amount of the lubricant therein, the said means being operable on a compression stroke to close the said communication, together with means operable on 115 this compression stroke to actuate the said means for feeding the desired amount of lubricant from the oil chamber to the cavity, whereby this amount of oil fed to the cavity may be carried on to the cylinder at the 120 next rarefaction stroke.
6. In a device of the class described, a body member having a cavity therein, an oil chamber within the body member, means contained within the oil chamber and entering the said cavity whereby a desired amount of lubricant may be passed from the chamber to the cavity at desired intervals, the said cavity being in communication with the atmosphere, as an air supply, and 130

also with the cylinder of an air compressor, means between the said cavity and the cylinder and operable by differences in pressure within the said cylinder whereby during a rarefaction stroke, the air may enter the cylinder through the said cavity and carry with it the lubricant present therein, the said means closing the said cylinder against communication with the cavity on a compression stroke of the cylinder, together with other means operable by the pressure of the cylinder for actuating the means between the oil chamber and the said cavity whereby the aforesaid desired amount of lubricant may be passed from the oil chamber to the cavity, which amount will be carried into the cylinder on the next rarefaction stroke.

7. In a device of the class described, a body member having a cavity therein and adapted to contain a desired amount of lubricant, an oil chamber in communication with the said cavity, means within the said communication and adapted to carry a desired amount of lubricant from the oil chamber to the cavity at certain intervals, the said cavity being in communication with the atmosphere, as an air supply, and being also in communication with the air cylinder of a compressor, the bottom member of the said cavity affording a valve seat, there being a valve adapted to engage the said seat and positioned between the cavity and the cylinder whereby on a rarefaction stroke the air may enter the cylinder through the cavity and there mix with the lubricant contained therein, the said valve being in open position, the said valve being moved to closed position on a compression stroke of the cylinder whereby the cylinder is held against communication with the atmosphere, together with other means operable by the said pressure, which means are adapted to actuate the said means for feeding the desired amount of lubricant from the oil chamber to the cavity, this feeding taking place during the compression stroke of the cylinder.

8. In a device of the class described, a body member having a cavity therein, the said cavity communicating at its upper portion with the atmosphere, and at its lower portion with the cylinder of an air compressor by means of a suitable valve, an oil chamber contained within the body member, means between the cavity and the oil chamber whereby a desired amount of lubricant may be passed from the oil chamber to the cavity at desired intervals, the said valve being movable on a rarefaction stroke to allow the air to enter the cylinder through the said cavity and carry with it the lubricant present therein, the valve being movable on a compression stroke to close the communication between the atmos-

phere and the cylinder, together with other means embodying a piston actuated by the pressure within the cylinder during a compression stroke and adapted to actuate means for passing the desired amount of lubricant from the oil chamber to the cavity at each compression stroke.

9. In a device of the class described, a body member having a cavity therein, the said body member also containing a source of oil supply, means between the said cavity and the said source whereby a desired amount of oil may be passed from the chamber to the cavity at desired intervals, the said cavity communicating with the atmosphere, and also communicating with the air cylinder of a compressor, the bottom of the cavity forming a valve seat having openings therein, together with a valve positioned adjacent the said openings and adapted to be moved into open position by the inflow of air to the cylinder on a rarefaction stroke whereby the air with the oil contained in the cavity mixed therewith may be passed to the cylinder, the said valve being movable into closed position on the compression stroke whereby the communication between the atmosphere and the cylinder may be closed, the cylinder being also in communication with a suitable piston, co-acting means between the said piston and the said means for passing the desired amount of lubricant from the oil chamber to the cavity, whereby during a compression stroke the piston will be operated, thereby operating the said feeding means in order to pass a desired amount of lubricant from the oil chamber to the cavity on each compression stroke, the said oil passing on to the cylinder on the next rarefaction stroke.

10. In a device of the class described, a body member having a cavity therein, the said cavity being adapted to contain a desired amount of lubricant, an oil chamber also within the said body member and a communicating passageway between the said cavity and the said chamber, a feed rod within the said oil chamber and entering the said passageway, the feed rod in one position being adapted to close communication between the oil chamber and the cavity, the feed rod being provided with a pocket whereby when it is in another position the oil contained in the pocket may be deposited in the cavity, the said cavity being in communication with the atmosphere as an air supply, the bottom of the cavity forming a valve seat having openings therein, there being a valve without the cavity and co-acting with the said valve seat, the valve being movable during a rarefaction stroke to place the atmosphere in communication with the cylinder through the said cavity whereby the air entering therein may in-

timately mix with the lubricant therein, the said valve being movable to closed position on a compression stroke, whereby the communication between the atmosphere and the cylinder is prevented, a piston contained within the cylinder which is in operable relation with the said cylinder of the air compressor and operable on a compression stroke thereof, means between the said piston and the said feed rod whereby when the piston is moved, the feed rod will also be moved to pass the desired amount of lubricant from the oil chamber to the cavity on each compression stroke.

15 11. In a device of the class described, the combination of a body member having a cavity therein, the said cavity being in communication with the atmosphere and with the air cylinder of the compressor, means whereby a desired amount of lubricant may be passed to the said cavity at desired intervals, a valve between the cavity and the cylinder of an air compressor, the said valve being movable into open position during a rarefaction stroke whereby air may be permitted to enter the cylinder through the cavity and mix with the lubricant contained therein, the said valve being movable to a closed position on a compression stroke of the cylinder, whereby the atmosphere is closed against communication with the said cylinder, together with adjustable means whereby the amount of lubricant passed to the said cavity at desired intervals may be varied.

12. In a device of the class described, a body member having a cavity therein, the said cavity being in communication with the atmosphere as an air supply, and also communicating with the air cylinder of a compressor, and a source of oil supply communicating with the said cavity, together with means whereby a desired amount of oil may be passed from the said supply to the said cavity, there being a valve between the cavity and the cylinder whereby on a rarefaction stroke the air may enter the cylinder through the cavity carrying with it the oil contained therein, the said valve being movable to closed position on a compression stroke whereby this communication is cut off, other means also operable by the pressure on the said compression stroke, for actuating the said feeding means, the said actuating means being adjustable in order to vary the amount of oil passed to the said cavity at desired intervals.

13. In a device of the class described, a body member having a cavity therein, the said cavity being adapted to contain a desired amount of lubricant, and being in communication with the atmosphere and with the cylinder of an air compressor, an oil chamber contained within the body mem-

ber, there being a communicating passage 65 between the oil chamber and the cavity, a feed rod having a pocket therein contained within the oil chamber and movable within the said passage, whereby at each movement of the feed rod the amount of oil contained within the pocket may be moved from the oil chamber to the said cavity, the said valve being movable on a rarefaction stroke to permit the air to enter the cylinder through the cavity and carry with it the oil contained therein, the said valve being movable to closed position during a compression stroke whereby communication between the atmosphere and the cylinder is prevented, another chamber contained within the body 80 member and having a piston therein, the said chamber communicating with the cylinder of the said compressor, a spindle having dogs at opposite ends thereof, one of the dogs adapted for engagement with the upper end of the said feed rod, the other dog being adapted for engagement with the upper end of the said piston whereby, on a compression stroke when the afore-mentioned valve is closed, the piston will be 90 moved and with it the feed rod in order to pass a desired amount of oil from the oil chamber to the cavity, this oil being carried on to the cylinder by the supply of air on the next rarefaction stroke.

14. In a device of the class described, a body member having a cavity therein, the said cavity being adapted to contain a desired amount of lubricant, and being in communication with the atmosphere and with the cylinder of an air compressor, an oil chamber contained within the body member, there being a communicating passage between the oil chamber and the cavity, a feed rod having a pocket therein contained within the oil chamber and movable within the said passage, whereby at each movement of the feed rod the amount of oil contained within the pocket may be moved from the oil chamber to the said cavity, the said valve 110 being movable on a rarefaction stroke to permit the air to enter the cylinder through the cavity and carry with it the oil contained therein, the said valve being movable to closed position during a compression 115 stroke whereby communication between the atmosphere and the cylinder is prevented, another chamber contained within the body member and having a piston therein, the said chamber communicating with the cylinder of the said compressor, a spindle having dogs at opposite ends thereof, one of the dogs adapted for engagement with the upper end of the said feed rod, the other dog being adapted for engagement with the upper 125 end of the said piston whereby, on a compression stroke when the afore-mentioned valve is closed, the piston will be moved and

with it the feed rod in order to pass a desired amount of oil from the oil chamber to the cavity, this oil being carried on to the cylinder by the supply of air on the next rarefaction stroke, together with adjustable means whereby the movement of the piston may be varied, thereby varying the movement of the said feed rod in order to vary the amount of oil conveyed from the

oil chamber to the feed pump on each movement of the feed rod.

In testimony whereof I have signed my name to this specification in the presence of two subscribing witnesses.
